US00D503927S

(12) United States Design Patent (10) Patent No.: **US D503,927 S**
Yoneyama et al. (45) Date of Patent: **** Apr. 12, 2005**

(54) ELECTRICAL CONNECTOR

(75) Inventors: **Kazuo Yoneyama**, Kyoto (JP); **Kenichi Sugino**, Kyoto (JP); **Tsushima Takada**, Kyoto (JP); **Takahide Kawanishi**, Osaka (JP)

(73) Assignee: **Hosiden Corporation**, Osaka (JP)

(**) Term: **14 Years**

(21) Appl. No.: **29/185,103**

(22) Filed: **Jun. 23, 2003**

(30) Foreign Application Priority Data

Dec. 27, 2002 (JP) 2002-037209

(51) LOC (7) Cl. **13-03**

(52) U.S. Cl. **D13/147**

(58) Field of Search D13/133, 146, D13/147, 154; 439/79, 108, 566, 607, 610, 660, 677
